UNITED STATES PATENT OFFICE

158,454

OFFSET TANDEM TRICYCLE

Stanley L. Glamb, Wayne, Mich., assignor to Dual
Remote Control Co., Inc., Wayne, Mich., a cor-
poration of Michigan

Application November 3, 1947, Serial No. 142,274

Term of patent 14 years

(Cl. D34—15)

To all whom it may concern:

Be it known that I, Stanley L. Glamb, a citizen of the United States of America, residing in the county of Wayne and State of Michigan, have invented a new, original, and ornamental Design for an Offset Tandem Tricycle, of which the following is a specification, reference being had therein to the accompanying drawing, forming a part thereof, wherein:

Figure 1 is a perspective view of an offset tandem tricycle showing my new design, and

Figure 2 is a cross sectional view taken on the line 2—2 of Figure 1.

I claim:

The ornamental design for an offset tandem tricycle, substantially as shown.

STANLEY L. GLAMB.
